UNITED STATES PATENT OFFICE.

HARRY WEARNE, OF RIXHEIM, GERMANY.

DESIGN FOR WALL-PAPER.

SPECIFICATION forming part of Design No. 29,660, dated November 8, 1898.

Application filed October 15, 1898. Serial No. 693,669. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a portion of a strip of wall-paper embodying the features of my design.

The design consists in the representation of a trellis in which rustic posts A appear,

together with an ornamental upright B, adjacent to one of the posts. Flowers of the rose type, also buds and sprays, are prominent between the posts and upon the upright, and vines are apparently trained upon the posts.

I claim—

The design for wall-paper herein shown and described.

HARRY WEARNE.
